UNITED STATES PATENT OFFICE.

SVEN A. JOHNSON AND HERMAN F. HOLMQUEST, OF BROOKLYN, NEW YORK.

COMPRESSOR.

Application filed May 9, 1923. Serial No. 637,781.

To all whom it may concern:

Be it known that we, SVEN A. JOHNSON and HERMAN F. HOLMQUEST, citizens of the United States, residing at Brooklyn, in the county of Kings and State of New York, have invented certain new and useful Improvements in Compressors, of which the following is a specification.

This invention relates to air pumps or compressors and has for its primary object to provide a rotary type pump designed to reduce friction to the minimum and simplify its construction without sacrificing efficiency.

One of the objects of our invention is to provide a rotary pump wherein a stationary, outer casing and inner drum are provided including a concentrically mounted hub or collar which is free to move with respect to the casing and the driven shaft so that a rolling motion is imparted to the said hub during the suction stroke.

A further object of our invention is to provide a rotary pump wherein an eccentrically mounted hub and loose ring are provided and are free to move with respect to a shaft and the outer casing during the suction stroke and while the outlet valve is raised from its seat.

We accomplish the above objects and others which will be more readily understood when taken in connection with the accompanying drawings, showing a preferred embodiment of our invention and wherein,

Figure 1 is a sectional end view of the pump showing the outlet valve seated.

Figure 2 is a similar view showing a different position of the eccentric and the loose hub and the valve unseated.

Figure 3 is a vertical section through the pump showing the relation of the driven shaft to the hub and eccentric.

Figure 4 is a detail view taken on the line 4-4 of Figure 3.

Referring now to the drawings wherein like reference characters designate corresponding parts throughout the several views, 5 designates the stationary outer casing or drum having an end boss 6 to receive the driven shaft 7, on which shaft the threaded plug 8 and packing glands 9 are provided as shown by Figure 3 of the drawings. An inner housing 10, mounted within the casing, is provided with a ball valve 11 that closes the outlet 12 during the operation of the pump. The casing is further provided

with an inlet or fluid intake 13 which communicates with the interior of chamber 14 of the casing and the outlet above referred to.

Keyed to the shaft 7, we have provided 60 an eccentric 15, which is adapted to impart a revolving motion to a loosely mounted hub or collar 16, which collar is of a width to extend between the inner and outer walls of the casing. The hub or collar is provided with recesses 18 to receive the coil springs 19 therein, said springs bearing against the loose ring 20, also free to move with respect to the casing and the eccentric. It will be noted that the loose ring is also substantially 65 the same width as the hub 16 and is further provided with a packing ring 22 which bears against the walls of the casing through the instrumentality of the horizontally extending springs 23 thus providing an air tight 70 joint within the chamber 14 during the revolving motion imparted to the hub by the eccentric. A valve seat 25 slightly above the inlet or fluid intake 13, receives a flapper suction valve 26 which is somewhat 75 curved on the bottom portion thereof and shaped to conform with the loose ring. A short shaft 27, connected to the valve 26 and extending outside the casing is adapted to receive a pin 28 to which a spring 29 is 80 connected so as to normally maintain the valve down at the inlet or suction stroke. A 85 short shaft 27, connected to the valve 26 and extending outside the casing is adapted to receive a pin 28 to which a spring 29 is 85 connected so as to normally maintain the valve down at the inlet or suction stroke. It will thus be seen that as the shaft 7 is 90 driven and the eccentric revolves, the loose hub and packing ring will be frictionally 95 carried therewith and rotate in the chamber 14 so that as the fluid is drawn into the chamber, it will be trapped and forced up to unseat the ball valve 11 and pass through the outlet 12. The flapper suction valve 95 prevents the return of the fluid drawn into the chamber 14, since the loose ring is of a diameter as to engage the outer end of the valve during the revolving motion thereof within the chamber 14. While we have 100 shown a flapper suction valve and a ball valve for the purposes above set forth, it will be readily understood that in actual practice other types of valves may be utilized to accomplish the same result and we therefore do not desire to be limited and restricted to the exact showing of this construction.

While we have illustrated and described 110 our invention with some degree of particularity, we realize that in practice various alterations therein may be made. We there-

fore reserve the right and privilege of changing the form of the details of construction or otherwise altering the arrangement of the correlated parts without departing 5 from the spirit of the invention or the scope of the appended claim.

Having thus described our invention what we claim as new and desire to secure by United States Letters Patent is:—

10 A pump of the class described comprising a casing, having an inlet and an outlet, a shaft mounted therein, an eccentric keyed to the shaft, a loose hub on the eccentric, a loose ring and resilient elements spacing

said ring from the hub, packing rings and 15 resilient elements within the sides of said rings, said rings, frictionally engaging the inner sides of the casing, an outlet valve and a resiliently held valve within the casing adjacent the said inlet. 20

In testimony whereof we affix our signatures in presence of two witnesses.

SVEN A. JOHNSON.
H. F. HOLMQUEST.
